[57] CLAIM

The ornamental design for a rack for crab utensils, as shown and described.

DESCRIPTION

FIG. 1 is a front elevation of a rack for crab utensils showing my new design, the mallet and knife shown in broken lines for clarity of illustration;

FIG. 2 is a top plan view thereof;

FIG. 3 is a bottom plan view thereof; and

FIG. 4 is a left side elevation thereof.

The undisclosed rear view is plane and unornamented.
